UNITED STATES PATENT OFFICE.

MORRIS M. WHITAKER, OF NYACK, NEW YORK.

DESIGN FOR AN ASH TRAY.

Application filed July 2, 1927. Serial No. 22,657. Term of patent 14 years.

To all whom it may concern:

Be it known that I, MORRIS M. WHITAKER, a citizen of the United States, and a resident of Nyack, county of Rockland, State of New York, have invented a new, original, and ornamental Design for Ash Tray, of which the following is a specification, reference being had to the accompanying drawing, forming part thereof.

Fig. 1 is a perspective view of an ash tray showing my new design.

Fig. 2 is a top plan view thereof.

I claim:

The ornamental design for an ash tray, as shown.

MORRIS M. WHITAKER.
